UNITED STATES PATENT OFFICE

AUGUSTE LANNOYE, OF GENVAL, BELGIUM

PROCESS FOR THE CONTINUOUS MANUFACTURE OF FLOOR COVERINGS

Application filed January 28, 1928, Serial No. 250,317, and in Belgium January 28, 1927.

The present invention has for its object to considerably increase the practical output in the manufacture of floor coverings made of a fabric or felt layer impregnated with some binding substance, preferably a bituminous compound such as petroleum asphalt, at the same time avoiding, to a great extent, the many accidents the workers are now liable to. The coverings prepared in this way are coated on both sides with successive layers of various substances, of printing colours and varnishes, whereafter they can be delivered and utilized for the covering of floors.

The successive operations were carried out, heretofore, separately, i. e. in a discontinuous manner. The felt was delivered up in rolls by a paper or cardboard manufacturer, and the rolls were submitted to a sequence of treatments, wherein they were first dipped into the bituminous bath, next to which the back of the sheet was given a colour, its other side being given a coating and then a print, to be finally varnished, cut to size, rolled up, packed for despatch, and so on.

That method of manufacture involves very serious drawbacks, viz.:

1. As any woollen fabric has much hygroscopic affinity, it readily takes up and retains the natural moisture of atmospheric air thus acquiring a fairly great percentage of water after several hours, say even as much as 8 to 10 per cent after a few days, according to the hygroscopic condition of the air.

Now, when undergoing the second phase of the treatment—the dipping into a bituminous bath kept in liquid state by the maintenance of about 200 degrees of heat—a portion of the water thus taken up from the air, was immediately re-converted into vapour, while a portion remained in the felt in the state of an occluded vapour which took the room of a certain amount of the bituminous binding between the woollen fibres; assuming the felt to be sectioned and examined through a powerful magnifying glass, quite a number of small hollow nodules or tiny cells will be seen between those woollen fibres and the bituminous agglutinate solidified. Assuming, conversely, a felt entirely free from water to have been dipped into the bath and

taken out, its section will show woollen fibres bound up by a quite homogeneous binding in solid state and free from any such cells (compare the sectional views of Fig. 8 and Fig. 9). As a result, the first-named felt, of a spongy appearance, will be, when cold, far more compressible than the second one, and it will, therefore, when utilized as a floor covering be far more liable to get and keep stamped marks caused by legs of heavy furniture or other heavy bodies laid on the floor. This drawback is a very serious one, and the marks thus printed into the covering will, of course, be less deep if the felt is free from moisture on being immersed, owing to the absence of such cells which are propitious to the penetration of heavy bodies and to the corresponding decrease of thickness of the floor-cloth.

2. That moisture taken up by the felt as a result of its getting vaporized in the bath, renders this bath much cooler;

3. The sequence of operations hitherto carried out result in a heavy loss of materials at every starting and every time a roll is at its end; the amount wasted is the more considerable as the quantity wound up has less length, and these rolls can have but a comparatively restricted length, as they would, otherwise, become so heavy as to exclude any possibility of being manipulated;

4. That sequence of operations require many hands, as the cloth must be wound up again after every operation; now, winding it up again means another waste, besides its requiring the employment of very precise and complicated machinery;

5. All of those operations require manual handling by workers, viz.:

a. Immersion into the bituminous bath at a high temperature, whereby accidents frequently occur; severe scalds are unavoidable whenever the operators are splashed with liquid, etc.

b. Introducing the cloth in coating machines or into printing cylinders, at the beginning of each roll, likewise brings about serious accidents by reason of hands or fingers getting squeezed and crushed.

As to winding up the covering after its

having been dried, this operation is another cause of dangerous manipulations by the workers' hands and arms. Between every two operations, rolls weighing thousands of pounds have to be carried off, and this is a further cause of accidents however cautious the operators may be.

6. On starting again motion of the coating, and mainly of printing machines, these get 10 frequently out of adjustment, whereby further waste cannot be avoided.

To eliminate all these drawbacks, the function of the plant for the manufacture of floor coverings should be uninterrupted, i. e., instead of having to stop work twenty or thirty times a day, the plant would simply be started every morning, or, in the case of a day-and-night running, one operation per week for starting it, would be sufficient.

20 We are to show and describe hereinafter, by way of a non-restrictive example, a diagram of plant executed in accordance with the present invention and enabling the operators to secure the result aimed at.

25 In the accompanying drawings:

Figs. 1 to 7 are vertical diagrams of a part of plant having its various machines shown in series with one another;

Fig. 5th is a modified plant wherein printing of the design would be effected by means of a machine equipped with a table and with a plane set of dies or stamps;

Fig. 8 is an enlarged sectional view through the cloth manufactured by a discontinuous 35 method as was previously practised, the objectionable vapour bubbles being shown occluded in the fabric;

Fig. 9, which is an enlarged sectional view of a cloth obtained by the novel method, 40 shows the homogeneousness secured by this method.

To carry the inventor's aim into practice, one has to erect a paper or cardboard machine comprising: a tub *a* containing the woolly 45 paper pulp; a strainer *b* for freeing the pulp from its impurities; a metal cloth *c* whereon the felt is to be applied; presses *d*, *e*, *f*, to squeeze the leaf in order to expel most of its water, all of which function uninterrupt- 50 edly, next to which comes a powerful drying plant comprising steam-heated cylinders *g*, the pressure applied being such as to make sure that the cloth will issue in a completely anhydrous condition, whereupon it will be 55 passed between two very flat and hollow platens *i*, wherein steam is circulated at a high pressure, so as to maintain the cloth very hot; this latter then enters into the bituminous bath *h*, whose correct temperature is 60 maintained by means of either gas burners or of any other contrivances; the felt being let out in a very hot state, will first undergo a pressure at *j* by two rolling cylinders similar to those of rolling mills, whereby its outer 65 surface will come out very polished. At the

point *k*, the cloth will be suddenly cooled down by the action of cold-air-blast devices or other contrivances such as artificial rain, cooling agents chiefly made of chloride of calcium or the like; the cloth then passes on to *l*, where its back is coated with some waterproof substance made of rosin (either natural or obtained by synthesis); it will then pass on to a suspending device *p* to stay there several hours for drying up that first coating. The cloth then passes between two rolling cylinders *m* to be next directed on to a second coating machine *n*, whereby its other side is coated with a pigmental colour, or chalk, or sulphate of barium and a siccative oil. The coating will be then dried up on a long suspending machine *p'* during 24 hours or so, under suitable conditions of temperature and additional action of either ultra-violet rays or of ozone. The sheet then passes again between two rolling cylinders *o* and from there over the alternate sides of the consecutive units of a set of cylinders *q*.

The uninterrupted sheet will then be given the printing by means of a rotary table *1* with cylindrical stamps *2* or by a plane machine comprising a plane table *3* and plane stamps *4*, as indicated in Fig. 5th. Upon either of these machines, the recto-side *r* of the cloth will be given the multicoloured design, whereupon the uninterrupted sheet will pass on to a drying plant *p''* serving to dry up the printing during a time of 12 to 24 hours. The felt, on leaving the driving apparatus, will pass on through two rolling cylinders *s* and over a row of cylinders *t* to the varnishing machine *u* by which the carpet will be imparted the required brilliancy.

Next thereto, a fourth drying-up stage in the suspending machine *p'''* followed by a 10 pressing between rolling cylinders *v* and then by winding up by a device here diagrammatically indicated at *w*, *x*, *y*; said felt is fed on at the same rate of speed in all of the devices.

A plant executed after this invention means obtention of considerable advantages, the most prominent of which are:

1. Formation of a felt far more homogeneous, and therefore less liable to being penetrated by the legs of pieces of furniture, etc.;
2. Maintenance of a constantly suitable temperature of the bath;
3. Great reduction of hand labour;
4. Risks of accidents to workers brought down to practically nothing;
5. Increased perfection in the work of all successively working machines, these being less liable to loss of adjustment;
6. Elimination of the many intermediary machines which were costly, dangerous and caused a great waste of material.

I claim:

1. A method of making slightly compressible floor coverings with impregnated felt

by successively making a web, drying, heating, impregnating, polishing, cooling, coating one side, drying, coating the other side, drying, pressing, printing, drying, pressing, varnishing, drying and pressing without reeling the web between the successive operations.

2. A method of making slightly compressible floor coverings with impregnated felt, characterized by continuously producing the raw web, drying, heating said web, immersing it in a bituminous bath, polishing, cooling it, coating its back side with a water proof substance, drying it, coating its front side with a colouring substance, drying it with the help of ultra-violet rays or ozone, pressing it, printing its front side, drying, pressing it, varnishing its front side, drying and pressing it, the successive operations being carried out uninterruptedly without intermediate reeling.

20 In testimony whereof I signed hereunto my name.

AUGUSTE LANNOYE.
